(57) **CLAIM**

The ornamental design for a license plate frame, as shown and described.

DESCRIPTION

FIG. 1 is a front elevational view of a first embodiment of a license plate frame showing my design;

FIG. 2 is a rear elevational view of the first embodiment;

FIG. 3 is a top plan view of the first embodiment;

FIG. 4 is a bottom plan view of the first embodiment; and FIG. 5 is a right side elevational view of the first embodiment, the left side elevational view being the mirror image thereof.

FIG. 6 is a front elevational view of a second embodiment of a license plate frame showing my design;

FIG. 7 is a rear elevational view of the second embodiment; FIG. 8 is a top plan view of the second embodiment;

FIG. 9 is a bottom plan view of the second embodiment; and FIG. 10 is a right side elevational view of the second embodiment, the left side elevational view being the mirror image thereof.

FIG. 11 is a front elevational view of a third embodiment of a license plate frame showing my design;

FIG. 12 is a rear elevational view of the third embodiment;

FIG. 13 is a top plan view of the third embodiment;

FIG. 14 is a bottom plan view of the third embodiment; and FIG. 15 is a right side elevational view of the third embodiment, the left side elevational view being the mirror image thereof.
